UNITED STATES PATENT OFFICE

2,377,672

COMMUNICATION SYSTEM

Richard H. Campbell, Racine, Wis., assignor to
Webster Electric Company, Racine, Wis., a corporation of Delaware

Application August 27, 1943, Serial No. 500,205

13 Claims. (Cl. 179—37)

The present invention relates to communication systems, and particularly to loudspeaking intercommunication systems.

An object of the present invention is to provide an intercommunicating system wherein one or more stations are provided with switch means whereby calls to the stations may be transferred to another station. As an illustration, the stations provided with the transfer switches may be executives' stations and the station to which the calls are transferred may be a station provided for the executives' secretary.

Another object of the present invention is to provide a system of the character specified wherein indicating means are provided at the executives' stations for showing when the apparatus thereat is conditioned for the transfer of calls to the secretary's station.

A further object of the present invention is to provide an arrangement of the character specified wherein the secretary can call the executive at any time.

Other objects and advantages of the present invention will become apparent from the ensuing description, in the course of which reference is had to the accompanying drawings, in which:

Fig. 1 is a diagrammatic representation of an embodiment of the invention in a communicating system of the character wherein communication is carried on in alternate directions between stations by the alternate manipulation of communication direction control switches thereat; and

Figs. 2 and 3 are diagrammatic representations of modified embodiments of the invention.

Referring now to Fig. 1, it may be noted that the system is of the multiple station type including four stations indicated by reference characters 1 to 4, inclusive. In order better to describe the operation and advantages of the invention, the system has been illustrated as including an executive's station 1, a subexecutive's station 4, a substation 2, and a secretary's station 3.

Much of the apparatus included at all four stations is identical, and in order to simplify the description thereof, only the apparatus at station 1 will be described and the same reference characters applied to the corresponding apparatus at the other stations. The communication apparatus is of the loudspeaking type, including an amplifier 10 having an input circuit 12 and an output circuit 14. A two-position communication direction control switch 16 is utilized to control the amplifier input and output connections, and also the connection of a loudspeaker 18 of the permanent magnet type to the input of the amplifier

and to an incoming communication circuit 20 to which the loudspeaker is connected through an adjustable volume control potentiometer 22.

In one position, the listen position, of the switch 5 16, the loudspeaker 18 is connected to the incoming circuit 20 through the switch blades 24, and in the other position, the talk position, the loudspeaker is connected to the input of the amplifier through circuit 12. In the listen position the output circuit is shorted by switch blade 26, and in the talk position the amplifier output is connected through the switch blade 28 to an output circuit 28.

The amplifier is supplied with power through a 15 power supply line 30. The communication direction control switch 16 is utilized also to cut off the amplifier plate voltage in the listen position of the switch. In the talk position the plate voltage circuit is completed through conductors 32 by 20 switch blade 34. Whenever the amplifier is in use the tubes are conditioned to be rendered immediately operative upon completion of the plate voltage circuit.

Each of the stations in the system has its individual incoming circuit, which may be termed 25 its "home line." The home lines for stations 1, 2, 3, and 4 are indicated by reference characters 41, 42, 43 and 44, respectively.

Each station is provided with station selector 30 switches in its output circuit 28 whereby that circuit can be connected to the home lines of the other stations. Thus, station 1 is provided with station selector switches 46, 48 and 50 individual to stations 2, 3 and 4, respectively; station 2 is 35 provided with selector switches 52, 54 and 56 individual to stations 1, 3 and 4, respectively; station 3 is provided with selector switches 58, 60 and 62 individual to stations 1, 2 and 4, respectively; and station 4 is provided with station selector switches 64, 66 and 68 individual to stations 40 1, 2 and 3, respectively.

The executive and subexecutive stations 1 and 45 4, respectively, are provided with switch means and are so connected with circuits leading to the secretary's station 3 that incoming calls to them may be transferred to the secretary's station. Thus, the stations 1 and 4 are provided with transfer switches 70 and 72 whereby the home lines 41 and 44 individual to stations 1 and 4 can be connected to the home line 43 individual to station 3. In the indicated position of switch 70 at 50 station 1, the station 1 home line 41 is connected to the incoming circuit 20 of station 1. In its other position switch 70 connects home line 41 to home line 43 of station 3. In similar manner,

the switch 72 at station 4 connects the station 4 home line circuit 44 to the incoming circuit 20 at the station in one position, and in its other position the station 4 home line 44 is connected to station 3 home line 43.

In order that an indication be given at the executive's and subexecutive's stations of the transfer of incoming calls to the secretary's station, there are provided indicator lights 74 and 76 at the two stations. These are adapted to be supplied with power from a suitable source (not shown) whenever the switches 70 and 72 are operated to transfer calls to the secretary's station. When the switches have been so operated, energizing circuits for the lamps are completed through switch blades 78 and 80 operating simultaneously with switches 70 and 72.

Another feature of the present invention resides in the provision of a circuit whereby the secretary may communicate with the executive at any time. The circuit includes the conductors 82 leading from selector switch 58 at station 3 to the incoming circuit 20 at station 1. Thus the secretary station may communicate with the executive station, no matter what the position of the transfer switch 70.

In describing the operation of the system it is assumed all the amplifiers 10 are supplied with power and conditioned for immediate operation upon actuation of switches 16 into their talk positions. Under normal conditions the switches are in their idle positions so that the loudspeakers 18 at the stations are connected to their individual home lines ready for the reception of calls from other stations.

It is assumed first that station 2 desires to communicate with station 1. The operator at station 2 first closes selector switch 52, thereby connecting the output circuit 28 at station 2 to interstation circuit 41 individual to station 1. Switch 16 at station 2 is then operated to its talk position, at which time the loudspeaker 18 is connected to the input of amplifier 10 through circuit 12 and the output of the amplifier is connected to circuit 28 through circuit 14. Thus station 2 is conditioned for transmission to station 1 through the amplifier at station 2 and circuit 41. After the call has been made the operator at station 2 releases the switch 16 thereat, thereby to condition the station for reception. To answer, the operator at station 1 first closes station selector switch 46 and then operates switch 16 to condition the station for transmission through the amplifier 10 and through interstation circuit 42 individual to station 1. Thereafter, communication may be carried on in opposite directions by alternate operation of the switches 16 at the two stations.

Stations 1, 2 and 4 may communicate with each other in the same manner as stations 1 and 2, and it is believed that further description of the manner in which this is done is not necessary.

In the event the operator at station 1, who, as heretofore indicated, may be an executive, leaves his office or does not desire to answer calls, he may operate switch 70 to transfer calls to station 3. When the switch 70 is operated the circuit 41 individual to station 1 is connected to the circuit 43 individual to station 3, and the operator at station 3 receives calls directed to station 1. In addition, the operator at station 3 receives calls directed to it over the interstation circuit 43 in the same manner as the other stations in the system. In the event the operator at station 3 receives a call, an answer can be made upon closure

of the station selector switch corresponding to the calling station and manipulation of communication direction control switch 16.

Station 3 can communicate with station 1 at all times, i. e., even when the transfer switch 70 has been operated at station 1. Assuming that the switch 70 has been operated to transfer calls to station 3, yet station 3 can call station 1. To do this, the operator at station 3 closes selector switch 58, thereby connecting the station 3 output circuit 28 to the loudspeaker 18 at station 1 through the interstation circuit 82, reception circuit 20 at station 1, the potentiometer 22, and the switch blades 24. If the operator at station 1 should be present to receive the call, then answer can be effected simply by closure of station selector switch 48 corresponding to station 3 and operation of switch 16 into its talk position, assuming, of course, that the operator at station 3 has released switch 16 thereat.

The operator at station 4 may similarly transfer calls to station 3 upon operation of the selector switch 72 thereat to connect interstation circuit 44 corresponding to station 4 to interstation circuit 43 corresponding to station 3. Station 3 can, however, call station 4 only in the ordinary manner; that is, through the interstation circuit 44 individual to station 4. Thus station 3 cannot communicate with station 4 when the transfer switch 72 has been operated. However, if desired, station 4 could be connected to station 3 in the same way as station 1, so that station 3 could call station 4 at any time.

The operators at the executive and subexecutive stations 1 and 4 are given an indication that incoming calls are being directed to the secretary's station by the indicator lights 74 and 76 which are energized when the transfer switches 70 and 72 are operated to transfer calls.

The present invention may be applied to other types of systems, and in Fig. 2 it is shown applied to a system of the type wherein each of the stations is provided with an amplifier to the input of which is connected a microphone, and with a loudspeaker utilized only for reception. The apparatus at each station may be of the type disclosed and claimed in my Patent No. 2,323,307, granted July 6, 1943.

The system of Fig. 2 is quite similar to that of Fig. 1, and like elements have been indicated by like reference characters. The system is characterized by interstation circuits individual to the various stations to which the loudspeakers 18 are normally connected, and by amplifiers 10 having their outputs connected to output circuits 28 leading to the station selector switches individual to the other stations and microphones 100 connected to their inputs. The amplifiers are normally conditioned for operation whenever power is supplied to them. The apparatus at each station includes also a high volume switch 102 normally conditioning the loudspeaker for reception at high volume and the amplifier for transmission at low volume. In its other position the switch 102 decreases the reception volume and increases the transmission volume so that other stations in the system may be called at high volume. The reception volume is controlled by switch blade 104 adapted normally to short circuit resistor 106 in series with the loudspeaker and adapted in operated position to remove the short circuit and to place a resistor 108 in parallel with the voice coil of the loudspeaker. The amplifier gain is controlled by switch blade 110 adapted in op-

erated position of the switch to decrease the gain of the amplifier.

The operation of the system shown in Fig. 2 is very similar to that of Fig. 1. In brief, one station may call another upon closure of the selector switch corresponding to the other station. For instance, station 2 may call station 1 upon closure of selector switch 52, thereby to connect loudspeaker 18 at station 1 to the output of amplifier 10 at station 2. To reply, the operator at station 1 closes selector switch 46, thereby to connect the amplifier at station 1 to the loudspeaker 18 at station 2. Thereafter communication may be carried on between the two stations without any further operation of switches. In order for one station to transmit to another at higher volume, the high volume switch 102 at the station may be operated, thereby to increase the amplifier gain and to decrease the reception volume.

If the operator at station 1 (or station 4) desires to transfer calls directed to it to station 3, the transfer switch 70 may be operated to connect interstation circuit 41 (individual to station 1) to the interstation circuit 43 individual to station 3. Thus any calls directed to station 1 are received at station 3, and the operator at station 3 can answer upon closure of the proper station selector switch—which would be switch 60 for station 1. In similar manner, the operator at station 4 may direct calls directed to it, to station 3.

The operator at station 3 may communicate with station 1 at all times—even when the transfer switch 70 has been operated. This results from the connection of circuit 82 to circuit 20 at station 1.

The present invention may be also embodied in systems of the type wherein communication is carried on between stations alternately in opposite directions over a single interstation circuit. A system of this character is shown in Fig. 3, to which reference is now had. Each of the stations includes an amplifier 10 normally supplied with power through the power lines 30 and having input and output circuits 12 and 14. One side of each of these circuits and of other circuits in the system is shown grounded, but it should be understood that two wire circuits may be utilized if desired.

Each of the stations is normally conditioned for the reception of calls from other stations by its communication direction control switch 120 comprising a pair of switch blades 122 and 124. In the listen position of the switch the loudspeaker 18 is conditioned for reception of calls through the amplifiers at other stations by a circuit including both switch blades 122 and 124 and the communication circuit 126. In the talk position of the switch the station is conditioned for transmission through its own amplifier, the loudspeaker 18 being connected to the input through switch 122 and the circuit 126 being connected to the output through switch blade 124.

The stations are connected by a number of interstation circuits 131, 132 and 133 individual to the stations 1, 2 and 3 of the system. The stations also include station selector switches normally connecting the circuits 126 thereat to their individual interstation circuits and operable to connect circuits 126 to the circuits individual to other stations in the system. Thus at station 1 the switch 134 normally interconnects circuits 126 and 131; at station 2 the selector switch 136 interconnects circuits 126 and 132; and at station

3 selector switch 138 interconnects circuits 126 and 133.

In this embodiment of the invention only station 1 has been provided with switch means for transferring calls directed to it to station 3. This transfer switch means is indicated by reference character 140, and it normally closes the circuit 126. When it is desired to transfer calls the switch is operated to another position to connect selector switch 134 (and also circuit 131 individual to station 1) to the interstation circuit 133 individual to station 3. Accordingly, any calls directed to station 1 are transferred to station 3.

Station 3 may call station 1 at any time, even though the transfer switch 140 at station 1 has been operated. This results from interconnecting stations 1 and 3 by a circuit 141 through which the circuits 126 at the two stations may be directly connected upon operation of the station 20 selector switch 138 at station 3.

Reviewing the operation of this system, one station may call another by operation of the selector switch to select the desired station, and upon operation of the communication direction control switch 124 to condition the station for transmission. Thus station 2 may call station 1 by operating selector switch 136 to complete a circuit to circuit 131 individual to station 1 and by operating switch 124 to its lowermost position. When these operations have been completed, loudspeaker 18 at station 2 is connected to the input of the amplifier 10 at the station and the loudspeaker 18 at station 1 is connected to the output of the amplifier through the interstation circuit 131, the selector switches 134 and 136, and the transfer switch 140 at station 1. To condition the circuits for a reply from station 1, the operator at station 2 releases switch 120 and the operator at station 1 operates the switch 120 thereat to its talk position. When this is done, the loudspeaker 18 at station 1 is connected to the input of amplifier 10 at the station and the output of the amplifier is connected to the loudspeaker 18 at station 2.

If the operator at station 1 desires to transfer incoming calls to station 3, it is necessary only to operate the transfer switch 140 to connect the interstation circuit 131 individual to station 1 to the interstation circuit 133 individual to station 3. Calls directed to station 1 are thereupon transferred to station 3 and communication may thereafter be held between the calling station and station 3 the same as heretofore described in connection with communication between stations 1 and 2.

Station 3 may communicate with station 1 at any time even though transfer switch 140 at the latter has been operated. When station 3 desires to communicate with station 1, the selector switch 138 is operated to interconnect circuits 126 and 141 and the communication direction control switch 120 at station 3 is operated to its talk position. Loudspeaker 18 at station 3 is thus connected to the input of amplifier 10 at station 3 and the output of the amplifier is connected to loudspeaker 18 at station 1. To condition the circuits for answer by station 1, the communication direction control switch at station 3 is released and the switch at station 1 is operated to its talk position.

Although the invention has been described in connection with specific details of preferred embodiments thereof, it should be understood that such details are not intended to be limitative

of the invention except in so far as stated in the appended claims.

Having thus described my invention, what I claim as new and desire to secure by Letters Patent of the United States is:

1. In a communication system, the combination including, a first station having a loud-speaking receiver and an interstation communication circuit individual thereto to which said receiver is connected to reception, a second station normally conditioned for reception, and means including switch means at the first station normally connecting said receiver to its interstation circuit and a circuit between said first and second stations controlled by said switch means for transferring calls directed to the first station to the second station.

2. In a communication system of the type wherein the stations are interconnected by pairs of interstation circuits over which communication is carried on in opposite directions, the combination including, a first station having switch means normally completing its reception circuit, and means including said switch means at the first station and a circuit controlled thereby for connecting the first station interstation reception circuit to the reception circuit of a second station.

3. In a communication system, the combination including, a first station having an interstation communication circuit individual thereto and communication direction control switch means for conditioning the circuit for reception thereover, a second station normally conditioned for reception, and means including switch means at the first station normally connecting said first station to its interstation circuit and a circuit between said first and second stations controlled by said switch means for transferring calls directed to the first station to the second station.

4. In a communication system, the combination including, a first station having a loud-speaking receiver and an interstation reception circuit individual thereto to which the receiver is connected, a second station normally conditioned for reception, and means including switch means at the first station in circuit with said receiver and normally connecting the receiver to said interstation circuit and a circuit between said first and second stations controlled by said switch means for connecting said reception circuit to the second station.

5. In a communication system, the combination including, a first station having a loud-speaking receiver and an interstation reception circuit individual thereto and communication direction control switch means for connecting the receiver to the circuit for reception thereover, a second station normally conditioned for reception, and means including switch means at the first station normally connecting said receiver to its interstation circuit and a circuit between said first and second stations controlled by said switch means for connecting said reception circuit to the second station.

6. In a communication system, the combination including, a first station having a loud-speaking receiver and an interstation circuit individual thereto over which communication is carried on alternately in opposite directions and communication direction control switch means for conditioning the station for reception or transmission over said circuit and normally connecting the receiver to said circuit for reception, a second station normally conditioned for reception,

and means including switch means at the first station normally connecting said receiver to its interstation circuit through said communication direction control switch and a circuit between said first and second stations controlled by said switch means for connecting said interstation circuit to the second station.

7. In a communication system, the combination including, a first station having an interstation communication circuit, a second station, means including switch means at the first station normally connecting said first station to said interstation circuit and a circuit between said first and second stations controlled by said switch means for connecting said interstation circuit to said second station, and means including another circuit between said stations for enabling the second station to communicate with the first irrespective of the position of said switch.

8. In a communication system, the combination including, a first station having a loud-speaking receiver and an interstation communication circuit to which the receiver is connected, a second station having receiving and transmitting means, means including a switch means at the first station normally connecting said receiver to said interstation circuit and a circuit between said first and second stations controlled by said switch means for connecting said interstation circuit to the receiving means at said second station, and means including another circuit between said stations for placing the transmitting means at the second station in circuit with the receiving means at the first station irrespective of the position of said switch means.

9. In a plural station communication system of the loudspeaking type wherein communication is carried on alternately in opposite directions over separate interstation circuits under the control of communication direction control switches at the stations, the combination including, a multi-position switch at one station completing the reception circuit for said station in one position, means including a circuit between said one station and the reception circuit for another station adapted to be completed by said switch in another position for transferring calls directed to the first station to the second station, and means including a circuit from the second station to the station side of the reception circuit at the first station for enabling the second station to communicate with the first station irrespective of the position of said multi-position switch.

10. In a plural station communication system of the loudspeaking type wherein communication is carried on alternately in opposite directions over separate interstation circuits, one of which includes a loudspeaking receiver, the combination including, a multi-position switch at one station connecting the receiver to said one interstation circuit in one position, means including a circuit between said one station and the reception circuit for another station adapted to be completed by said switch in another position for transferring calls directed to the first station to the second station, and means including a circuit from the second station to said receiver for enabling the second station to communicate with the first station irrespective of the position of said multi-position switch.

11. In a plural station communication system of the loudspeaking type wherein communication is carried on alternately in opposite directions

over a single interstation circuit under the control of communication direction control switches, the combination including, a multi-position switch at one station completing the reception circuit for said station in one position, means including a circuit between said one station and the reception circuit for another station adapted to be completed by said switch in another position for transferring calls directed to the first station to the second station, and means including a circuit from the second station to said receiver for enabling the second station to communicate with the first station irrespective of the position of said multi-position switch.

12. In a communication system, the combination including, a first station having an interstation communication circuit, a second station, means including a switch means at the first station normally connecting said first station to said interstation circuit and a circuit between 20

said first and second stations controlled by said switch means for connecting said interstation circuit to said second station, and signal means at said first station controlled in response to the position of said switch means for indicating the condition of said switch means.

13. In a communication system, the combination including, a first station having an interstation communication circuit, a second station, means including a switch means at the first station normally connecting said first station to said interstation circuit and a circuit between said first and second stations controlled by said switch means for connecting said interstation circuit to said second station, signal means at said first station, and switch means controlling said signal means operable simultaneously with said first mentioned switch means for indicating the condition of said switch means.

RICHARD H. CAMPBELL.
